UNITED STATES PATENT OFFICE

156,341

HAIR DRIER

Alfonso Iannelli, Park Ridge, Ill., assignor to John Oster Manufacturing Company, Racine, Wis.,
a corporation of Wisconsin

Application July 26, 1948, Serial No. 147,787

Term of patent 14 years

(Cl. D86—10)

To all whom it may concern:

Be it known that I, Alfonso Iannelli, a citizen of the United States, residing at Park Ridge, in the county of Cook and State of Illinois, have invented a new, original, and ornamental Design for a Hair Drier, of which the following is a specification, reference being had to the accompanying drawings, forming part thereof.

I claim:

The ornamental design for a hair drier, substantially as shown.

ALFONSO IANNELLI.
